The ornamental design of the combined snowmobile ski and lost motion handle, as shown and described.

DESCRIPTION

FIG. 1 is a perspective view of the combined snowmobile ski and lost motion handle of our new design;

FIG. 2 is a top plan view thereof;

FIG. 3 is a side elevational view thereof, the opposite side being a mirror image thereof;

FIG. 4 is a bottom plan view thereof;

FIG. 5 is an enlarged front elevational view thereof;

FIG. 6 is an enlarged rear elevational view thereof;

FIG. 7 is an enlarged side elevational view, partly sectioned, of the forward section of the combined snowmobile ski and handle;

FIG. 8 is an enlarged section view taken along the line 8—8 of FIG. 2;

FIG. 9 is a prospective view of a modification of the combined snowmobile ski and lost motion handle of FIG. 1;

FIG. 10 is a top plan view of FIG. 9;

FIG. 11 is a side elevational view of FIG. 9, the opposite side being a mirror image thereof;

FIG. 12 is a bottom plan view of FIG. 9;

FIG. 13 is an enlarged front elevational view of FIG. 9;

FIG. 14 is an enlarged rear elevational view of FIG. 9;

FIG. 15 is an enlarged side elevational view, partly sectioned, of the forward section of the combined snowmobile ski and handle of FIG. 9; and,

FIG. 16 is an enlarged sectional view taken along line 16—16 of FIG. 9.

The design of the combined snowmobile ski and lost motion handle is characterized with upwardly arched handle having a general transverse oval shape rear side with an oblong slot for accommodating a transverse bolt connecting the rear end of the handle to the ski.
